UNITED STATES PATENT OFFICE.

JOHN TAYLOR, OF COLONIE, NEW YORK.

TRUCK.

1,048,375.

Specification of Letters Patent. Patented Dec. 24, 1912.

Application filed September 16, 1912. Serial No. 720,610.

To all whom it may concern:

Be it known that I, JOHN TAYLOR, of Colonie, in the county of Albany and State of New York, have invented certain new and useful Improvements in Trucks; and I hereby declare that the following is a full, clear, and exact description thereof, reference being had to the accompanying drawings, which form part of this specification.

10 This invention is a novel improvement in trucks for railway cars and particularly relates to the means for suspending the spring planks or bolsters of such truck.

The invention consists in the novel construction of the hanger-supports and hangers by which the spring plank or bolster are suspended upon the truck frame, and is particularly designed for use with the form of trucks shown in my Patents Nos. 674,224

20 and 674,225, dated May 14, 1901, but it is also adapted for use with the variety of trucks of other constructions and for use where strong swinging suspension devices are needed.

25 In the ordinary construction of car trucks the spring planks and bolsters have been suspended from the truck frames by means of pairs of links, or by means of U-shaped hangers, which latter are usually suspended

30 from the hanger-supports by means of nuts on their upper ends. In the practical use of such U-shaped hangers considerable difficulty has been experienced as the jarring of the truck caused by the wheels running

35 over rough joints, switches and crossings, tends to crystallize the hangers and cause them to break at the threaded portion; and where the U-shaped hangers are suspended from the supports by passing through open-

40 ings therein, the supports are apt to fill up with mud and slush and obstruct the free swinging motion of the hanger, which is necessary when the truck is rounding curves, and this produces severe strains

45 upon the hangers at their points of suspension from the hanger supports, and has frequently caused breakage of the hangers and resultant loss and damage.

In my present invention all such difficulties are overcome and avoided by reason of the novel construction of the hanger-support and hanger.

50 The invention in brief comprises a U-shaped hanger support which is adapted to be secured to and preferably between the top side bars of the truck frame and to sup-

port a rectangular link hanger freely suspended from such support and preferably formed of one continuous piece; and when properly engaged with such, a hanger-support is free to swing laterally and it is impossible for mud or dirt to bind such hanger or interfere with the free swing of the same.

Another important advantage of the novel construction of hanger-support and hanger is that it overcomes the tendency of the spring plank to swing laterally or longitudinally of the truck with the starting or stopping of the latter.

I will explain the invention in detail as applied to a truck of the type shown in my Patent #674,224 and will set forth in the claims the essential construction for which protection is desired.

Referring to the accompanying drawings: Figure 1 is a perspective view of part of a car truck equipped with my invention, one of the top side bars of the frame being broken away to show the attached hanger support more clearly. Fig. 2 is an enlarged transverse vertical section on line 2—2, Fig. 1, and Fig. 3 is a sectional view on line 3—3, of Fig. 2.

In the drawings, A, A, designate adjacent pedestals of the side frame of the truck which may be connected at the top by parallel side bars B, and at the bottom by a tie-bar C. The bars B of opposite side frames of the truck may be connected by transverse tie-bars H, between which lies the bolster S, which may be supported upon springs R mounted upon a spring plank O which is itself suspended from the bars B, intermediate the wheels of the truck, by suitable hangers.

The parts thus far described may be constructed substantially as shown and described in my Patent #674,224 above referred to; but may be of any other suitable construction.

Between the top bars B of each side frame, and at a point intermediate the wheels of the truck, and adjacent the ends of the tie-bars H, is secured one of my novel hanger supports 1; such hanger-support is preferably U-shaped in cross section and is of a width to fit closely between and against the inner sides of the adjacent bars B; and this hanger-support is provided at its upper edges with lips 1^a which are adapted to project over and rest upon the upper edges of the bars B. The hanger supports are se-

cured to the bars B by means of through bolts 2 which pass through corresponding openings in the bars B and the hanger as shown, and may be secured by nuts 2^a or other suitable means. A spacing member 3 is inserted in the hanger and preferably supported on the bolts 2, and said spacing member prevents distortion of the hanger-support when the bolts 2 are tightened to clamp the hanger-support securely in position.

Suspended from each hanger support is a link hanger 4 which is preferably forged out of a round steel rod, and is like a rectangular frame in shape; the ends and sides 15 of said hanger being preferably forged together so as to make the hanger solid or continuous. One end of this hanger is placed in the U-shaped hanger-support 1 and it is lowered between the bars B before the 20 hanger-support is bolted in position; the hanger is confined in the hanger-support by means of the bolts 2 which, however, do not interfere with the free swinging movement of the lower part of the hanger.

25 As shown the ends of the spring plank O are secured to and supported upon the lower ends of the hangers 4, substantially as described in my Patent #674,224 aforesaid; or in any other suitable way so the spring plank 30 can have the necessary free longitudinal swing transversely of the truck.

It will be seen that in my invention it will be impossible for any collection of dust or dirt in the hanger support to interfere 35 or obstruct the free swinging movement of the hangers; that there is nothing to break about the hanger unless the body thereof gives way; that no pins or bolts are directly connected with the hanger and that all the 40 weight is transmitted from the hanger to the bottom of the hanger-support; and that the hanger has a long broad bearing in the hanger-support and by reason of such bearing the tendency of the spring plank to 45 swing or move laterally in a direction longitudinally of the truck during the stopping or starting of the car will be overcome.

The hanger-support might be forged like the hanger or both may be made of malleable 50 iron.

My novel hanger-support and hanger are

less expensive to manufacture and more easily assembled and connected to the truck frame, than the forms of hangers and hanger supports commonly employed in truck constructions. 55

What I claim is:

1. In combination with the parallel side bars of a truck; a U-shaped hanger-support secured to and between said bars, a frame-shaped hanger having its upper member lying within and extending longitudinally through said support and suspended thereby from said support; and a member supported on said hanger. 60

2. In combination with a truck frame having parallel side bars, U-shaped hanger supports bolted to and between the said side bars; rectangular link-shaped hangers having their upper members lying within and extending longitudinally through said supports and suspended therefrom; spacing members in said supports; a spring plank supported on said hangers; springs on the plank; and a bolster mounted on the springs. 70

3. The combination with a truck frame having pairs of parallel bars at each side, of opposite hanger supports attached directly to and between the pairs of bars at the sides of said frame, a frame-shaped hanger having its upper member extending across and resting within each support and suspended thereby from said support, and a bolster carried by said hangers. 80

4. In combination with a truck frame having pairs of parallel side bars at each side, a U-shaped hanger support bolted to and between the side bars at each side of said frame, a frame-shaped hanger having its upper member lying within and extending longitudinally through said support and suspended thereby from said support, a spacing member in said support above the hanger member, and a bolster carried by said hangers. 85

In testimony that I claim the foregoing as my own, I affix my signature in presence of two witnesses.

JOHN TAYLOR.
